(57) CLAIM

The ornamental design for a jewelry display, as shown and described.

DESCRIPTION

FIG. 1 is a perspective view of the jewelry stand showing my new design;

FIG. 2 is a left side perspective view thereof;

FIG. 3 is a right side perspective view thereof;

FIG. 4 is a rear perspective view thereof; and,

FIG. 5 is a top perspective view thereof.

The broken line showing of the feet of the jewelry display is included for the purpose of illustrating environmental structure and forms no part of the claimed design.

1 Claim, 5 Drawing Sheets
